[57] ABSTRACT

A parking brake assembly wherein the main lever assembly is longitudinally divided so that the operating components of the assembly can be positioned in one of the divided members and the other half is secured thereto which enables automatic assembly of the components.

PARKING BRAKE OPERATOR LEVER

BACKGROUND OF THE INVENTION

This invention relates to improvements in parking brake operating levers. Because of labor shortages, it has become increasingly important to substitute manual work with automatic machines in the production of mass-produced assemblies for automobiles and the like. It is difficult to automate the assembly of many devices where a plurality of operating components is involved. For instance, in structures relating to parking brake operating levers, it has heretofore been impossible to efficiently assemble the lever proper because of the multiple supply directions for the assembly of the component parts.

SUMMARY OF THE INVENTION

An object of this invention is to provide a parking brake operating lever which can be automatically assembled. The lever proper is divided lengthwise for these purposes.

BRIEF DESCRIPTION OF DRAWINGS

These and other objects of the invention will become more apparent to those skilled in the art by reference to the following detailed description when viewed in light of the accompanying drawings wherein:

FIG. 1 is a vertical cross section;

FIG. 2 is an end view taken from the right of FIG. 1;

FIG. 3 is a view of the major component parts; and

FIG. 4 is an exploded perspective showing several principle components.

Referring now to the drawing wherein like numerals indicate like parts, the numeral 1 indicates a parking brake operating assembly of this invention. The assembly includes a cylindrical portion 3 having at one end a downwardly extending triangular-shaped base portion 2. The lever assembly is divided longitudinally into symmetrical parts *a* and *b*. The base 2 is apertured at its lower end to receive a braking cable to perform a braking function in the conventional manner. Extending inwardly from portion *a* are a pair of pins 4 and 5 reduced in diameter at their outer ends to be received by matching apertures in the base portion 2 of part *b*. A ratchet fitting 9 notched at area 10 is secured to the vehicle chassis *c* by bolts as shown in FIG. 1.

Between members *a* and *b* is a pawl member 11 mounted for pivotal movement about pin 5 and having a tooth for engagement with the ratchet portion 10. At its other end, the pawl 11 is pivotally secured to a rod 8 having a button 13 at its outer end. A handle member 12 of plastic or rubber is secured about the cylindrical portion 3. Secured within the cylindrical portion 3 near the button 13 is an abutment 14. A coil spring 7 is disposed between the abutment 14 and the button 13 and acts to bias the pawl into engagement with the ratchet. As can be readily understood, a depression of the button 13 against the bias of the spring permits the pawl to disengage the ratchet portion. The lever assembly itself is mounted for pivotal movement about pin 4 when the ratchet is disengaged. As will be readily understood by those skilled in the art, a pivoting movement of lever 3 when the pawl is disengaged will permit the base portion 2 to transmit a braking or release movement to a cable attached thereto. This brake as-

sembly is generally referred to by the numeral 6. The numeral 15 indicates a tubular cover which encloses the cylindrical portion 3 by sliding it from the front after joining side *b* to the receiving side *a* of said lever from the identical side with said braking mechanism 6 and clamping and securing the tip portions of said pivot pins 4, 5 which protrude from the surface of the base portion. The tube covers the joint which is unfavorable to the vehicle standard as it is exposed in the longitudinal direction of the upper portion of said lever proper 1, and retains the joint between said receiving side *a* and the joint portion side *b* more firmly to prevent a decrease in strength. The brake operating lever is generally coated with a chrome plating giving the lever of this invention an effect similar to an expensive chrome plating by making it with a stainless steel sheet.

The covering method may be carried out either by bending projecting members provided at the appropriate end portions inwardly of the lever proper 1, forming the lever by an elastic material and clamping from the external side, or applying a bonding agent on an inner periphery to bind them. The numeral 12 indicates a handle grip which is inserted with pressure 25 from the forward portion into the tip portion of the cylindrical portion 3, and is effective in retaining the joining of said receiving side *a* and the joint portion side *b* more firmly, but it may not be used when the cover 15 encloses the cylindrical portion. It should be noted that the pivot pins 4 and 5 can be fixed to the side *b* or the fitting member 9 of the braking mechanism 6 without rising and fixing to the one of the receiving sides *a* of the lever proper 1, or can be inserted from its one side 30 after jointing the side *b* to the side *a* without fixing to either side. By employing a divided lever this invention enables the assembly of the component parts, namely, the fitting member 9, the braking mechanism 6, the operating lever 8, and the divided lever proper 1 to the other divided portion by supplying them from the identical direction. This makes the automation of the assembly of parts of said operating lever. Furthermore, the operating lever of this invention can be applied to the braking mechanism 6 which is an important portion 35 of the lever to a wide range not only for the above-mentioned ratchet system but also for a wedge system.

In a general manner, while there has been disclosed an effective and efficient embodiment of the invention, it should be well understood that the invention is not limited to such an embodiment as there might be changes made in the arrangement, disposition, and form of the parts without departing from the principle of the present invention as comprehended within the scope of the accompanying claims.

We claim:

1. A brake assembly particularly for use to move an operating member of a vehicle parking brake mechanism comprising
a fitting secured to the chassis of the vehicle,
a ratchet formed on a surface of said fitting,
an elongated lever member longitudinally divided
into first and second sides disposed on both sides
of said ratchet,
a tubular hand-grip forming one end of said lever,
a base portion at the other end of said lever member
to which said operating member of said braking
mechanism is adapted to be attached,

first means pivotally supporting said lever member to said fitting between said one end and said base, a pawl having a tooth for engagement with said ratchet,
second means pivotally mounting said pawl between said sides,
third means within said hand-grip for selectively moving said pawl to and from locking engagement

with said ratchet.

2. The invention of claim 1 wherein said first means includes a pin extending between said first and second sides.

5. 3. The invention of claim 2 wherein said second means includes a second pin extending between said first and second side.
